US00D633495S

(12) **United States Design Patent**
Yoon et al.

(10) **Patent No.:** **US D633,495 S**
(45) **Date of Patent:** **** Mar. 1, 2011**

(54) **ACCESS DEVICE**

(75) Inventors: **Henry Yoon**, Gimpo (KR); **Chang Yu**, Ansan (KR); **Kevin Strohmeyer**, Lafayette, CA (US)

(73) Assignee: **nComputing, Inc.**, Redwood City, CA (US)

(**) Term: **14 Years**

(21) Appl. No.: **29/360,539**

(22) Filed: **Apr. 27, 2010**

(51) **LOC (9) Cl.** **14-02**

(52) **U.S. Cl.** **D14/356**; D14/240

(58) **Field of Classification Search** D14/300-302, D14/313, 314, 341, 348-370, 383, 385, 432, D14/435, 436, 496, 125, 135, 137, 155, 167, D14/168, 214, 230, 231, 233, 235, 237, 240-242, D14/299; D3/201, 273; D18/56; D10/65, D10/75, 78; D13/103, 149, 162, 184, 199; 361/679.31-679.45, 752; 711/100, 115

See application file for complete search history.

(57) **CLAIM**

The ornamental design for an access device, as shown and described.

DESCRIPTION

FIG. 1 is a front view of an access device showing our new design;

FIG. 2 is a rear view of the access device, according an example embodiment;

FIG. 3 is a left-side view of the access device, according to the example embodiment;

FIG. 4 is a right-side view of the access device, according to the example embodiment;

FIG. 5 is a top view of the access device, according to the example embodiment; and,

FIG. 6 is a bottom view of the access device, according to the example embodiment.

The broken lines in the drawings are for the purpose of illustrating unclaimed portions of the access device and form no part of the claimed design.
